UNITED STATES PATENT OFFICE

NORMAN DESSAUER, OF NEW YORK, N. Y., ASSIGNOR TO THE INTERNATIONAL SEAL AND KNOT PROTECTOR CO., OF NEW YORK, N. Y., A CORPORATION OF NEW YORK

SEAL

Application filed January 11, 1929. Serial No. 331,873.

This invention relates to seals of that type in which there is a metal strap adapted to be extended through the part to be sealed and to have the ends of the strap permanently secured together so that they cannot be separated without mutilation or the leaving of tell-tale evidence of tampering.

One object of my invention is to so construct the parts that the end portions of the strap may be formed by a single stamping operation, and the ends of the strap secured together by a comparatively simple compressing action.

A further object is to provide a construction in which all parts of the seal are constructed from a single piece of sheet metal, comparatively simple in design, and requiring simple and inexpensive dies.

As one important feature of my invention one end of the metal strap is provided with a pair of cups adapted to telescope one within the other, and the opposite end of the strap is provided with a head which will fit within these cups so that when the sealing operation is effected the head is gripped within both of the cups and the separation is thus rendered doubly difficult, if not impossible.

In the accompanying drawings I have illustrated one embodiment of my invention.

In these drawings:

Fig. 1 is a perspective view of the seal in open position;

Fig. 2 is a perspective view with the head at one end of the strap in one of the cups;

Fig. 3 is a perspective view similar to Fig. 2, but showing the next step in the operation of sealing;

Fig. 4 is a perspective view similar to Fig. 3, but after the ends are permanently connected; and

Fig. 5 is a transverse section on the line 5—5 of Fig. 4, but upon a considerably larger scale.

In my improved construction I employ a sheet metal strap having a body portion 10 of suitable width, length and thickness in accordance with the character of the device in connection with which the seal is to be employed. The metal is of such thickness and brittleness that it is readily broken if an at-

tempt be made to straighten it after once it has been bent to sealed position.

To facilitate the bending of the seal intermediate of its ends and to insure the proper positioning of the ends in respect to each other, the body of the strap is weakened, as for instance, by means of a hole 11 leaving narrow bendable portions 12 upon each side thereof. The weakness resulting from the hole results in the proper location of the bending, and the narrowing of the portions 12 increases the fragile character and better insures the breaking if an attempt be made to straighten the parts after they are once bent.

At one end of the strap, there is provided a head portion 13 separated from the body of the strap by a narrow neck portion 14. Preferably the head is substantially circular, although of course this is not of vital consequence.

At the opposite end, the strap is provided with a pair of cups 15 and 16 arranged in series. The first cup 15 has a bottom wall and upstanding edges and is connected to the body portion by a neck 17. The cup 16 is slightly smaller and is connected to the cup 15 by a neck portion 18 which may be notched to increase fragility and locate the proper point of bending. The neck portion 18 preferably extends flush with the bottom wall of the cup 16 and extends from the upper edge of the peripheral wall of the cup 15 at a point diametrically opposite to the neck 17.

In the operation of my improved device, the strap is passed through the staple, loop or other part of the apparatus to be sealed, and is then bent so that the head 13 comes within the cup 15, as shown in Fig. 2. The parts are so proportioned that if the strap be bent at the hole 11 the head 13 will come into the cup 15, as shown in Fig. 2. The next step in the operation is to bend the neck 18 so that the cup 16 telescopes within the cup 15, and upon and preferably around the head 13. The parts will then be in the position shown in Fig. 3. The two cups are then gripped within a suitable compressing device and sufficient pressure is brought to swage over or bend in the walls of both cups. The

bending may bring the parts to the position shown in Fig. 5 in which it will be noted that the side walls of the cup 16 slide underneath the head 13 so as to grip the latter, while the 5 side walls of the cup 15 are bent in to lie on top of the cup 16. Any attempt to open the seal will thus necessitate the careful straightening up of the walls of the cup 15, difficult removal of the connected cup 16 and head 13, and the separation of these parts.

10 As the edge walls of the cup 16 will come underneath the head 13, it will be difficult, if not impossible, to get at these edges in such a way as to straighten them without breaking 15 the seal, either at the neck 18, the narrow portions 12, or the neck 17.

15 It will be noted that the entire strap may be made of a single stamping operation as both cups have their peripheral walls extending in the same direction, and the diameters of the cups are such that the strip of material from which the seal is made is no wider than the body portion 10.

20 By reason of the interlocking of the head 25 13 with the two cups when their flanges face in opposite directions, and by reason of the narrow neck connecting the two cups, the device is thoroughly tamper proof.

25 Having thus described my invention, what 30 I claim as new and desire to secure by Letters Patent is:

35 1. A seal comprising a strap of sheet metal, including a body portion, a substantially circular head at one end in the plane 40 of the body portion and connected to the body portion by a narrow neck, a cup at the opposite end, said cup having a bottom wall in the plane of the body portion and connected thereto by a narrow neck and having 45 an upstanding peripheral wall, the internal diameter of said cup being greater than the external diameter of said head, and the peripheral wall of said cup being bendable into position above said head when the latter is placed within said cup with said necks superposed.

50 2. A seal including a strap of sheet metal having a pair of cups at one end thereof, each having a bottom portion and an upstanding peripheral wall, a neck connecting said cups and extending from the upper edge of the 55 peripheral wall of one cup to the bottom of the other cup, a neck connecting the body portion to the bottom of the first mentioned cup, the diameter of the cups being such that one may be telescoped within the other upon the bending of the first mentioned neck, and a head at the opposite end of said body portion and adapted to fit within one of said 60 cups.

65 Signed at New York, in the county of New York and State of New York this 10th day of January, A. D. 1929.
